POODLE DOG FLOWER ARRANGEMENT

Raymond Prybella, 1533 S. 4th St.,
Philadelphia, Pa. 19147

Filed Aug. 5, 1969, Ser. No. 18,547

Term of patent 14 years

Int. Cl. D11—04

U.S. Cl. D29—1

Fig. 1

FIG. 1 is a front elevational view of a poodle dog flower arrangement showing my new design; and FIG. 2 is a side elevational view thereof.

I claim:

The ornamental design for a poodle dog flower arrangement, as shown.
